ATTORNEY

UNITED STATES PATENT OFFICE.

LAWRENCE F. OTTEN, OF NEWPORT, KENTUCKY.

BELT BUCKLE.

Application filed March 4, 1922. Serial No. 540,970.

To all whom it may concern:

Be it known that I, LAWRENCE F. OTTEN, a citizen of the United States, residing in Newport, in the county of Campbell and State of Kentucky, have invented certain new and useful Improvements in Belt Buckles, of which the following is a specification.

My invention relates to belt buckles for personal wear.

The objects of my invention are to provide a simple and economical construction and one which is positive and efficient in action and use and also to simplify and improve the details of construction and arrangement.

My invention consists in the combination and arrangement of parts and in the details of construction as herein set forth and claimed.

In the drawings:

Fig. 1 is a front perspective of my improved buckle with the belt attached thereto and in engaged position;

Fig. 2 is a rear elevation of buckle in the position illustrated in Fig. 1;

Fig. 3 is a longitudinal section on the line 3—3 of Fig. 2 showing the loop actuating member and gripping device in elevation and the latter in belt gripping position;

Fig. 4 is a view similar to Fig. 3 except that the gripping device is disengaged to permit the belt to be inserted or withdrawn;

Fig. 5 is a cross section on the line 5—5 of Fig. 2, showing the gripping device in elevation;

Fig. 6 is a perspective view of the gripping device; and

Fig. 7 is a perspective view of the gripping device actuating loop to which one end of the belt is attached.

In the embodiment of my invention as illustrated and which shows a preferred construction my improved belt buckle comprises a metal plate 11 of any suitable design or shape with integrally formed sides 12 inturned at approximately right angles to plate 11 each having an integrally formed lip 13 extending toward each other adjacent one end of the buckle and parallel to plate 11 thereon forming a channel 14 adapted to act as a guide way for positioning the free end of the belt 15. I have illustrated this plate as of having a rounded or convex front with the laterally projecting ears 16 at each side of plate 11 and near one end

thereof to provide a simple and convenient means for holding pivot pin 17 in place. Ears 16 are provided with conical shaped outwardly extending projections 18 each having a hole 19 therethrough.

Pin 17 is reduced at each end to form shoulders 20 and extensions 21, said shoulders being adapted to snugly engage conical projections 18 respectively and said extension holes 19 thereby making a secure fastening for said pivot pin.

The gripping device 22 is of semi-cylindrical shape with connecting or gripping surface 23 preferably roughened or grooved longitudinally and is of proper length to permit it to be placed between ears 16 of plate 11. The bearing 24 is integrally formed at one side of gripping member 22 by projections 25 extending outwardly from the regular plane of said gripping device at each end and through the center and projections 26 extending inwardly from the regular plane of said gripping member between its ends to receive pivot pin 17 and by which said gripping device is pivotally connected to plate 11. A hinge connection formed at one side of the gripping device produces an eccentric action when moved by means of actuating loop 27 which is provided with eyes 28 mounted on pin 17 in slots 29 and between outward projections 25 and inward projections 26 whereby it is positioned from lateral movement. Actuating loop 27 is adapted to have one end of the belt 15 secured thereto as shown in Figs. 2, 3 and 4. Sides 30 of actuating loop 27 are adapted to rest on edge 31 of gripping device 22 when the latter is in closed or engaged position as shown in Fig. 3 and to rest on edge 32 thereof when forced open or when disengaged as shown in Fig. 4 thereby producing a very positive action on the gripping member whereby it is forced into and out of belt holding position. Said edges 31 and 32 are spaced apart so as to provide a certain degree of independent action or movement of the gripping device with relation to the actuating loop.

Thus it will be seen that a belt buckle constructed according to my invention is of very simple and economical construction and one which is easy and convenient to operate as well as one which is adapted to securely hold the belt in any adjusted position desired.

While I have shown this particular con-

struction and arrangement of parts it will be apparent that my invention can be constructed of some modified form without going outside of the scope or spirit of my invention.

What I claim as new and desire to secure by Letters Patent is:

1. In a belt buckle, a plate having upturned ears, a pin secured to said ears, a curved gripping device mounted on said pin and adapted to secure the belt, a loop pivotally mounted on said pin and having arms adapted to engage the respective longitudinal edges of said gripping device between its pivotal connection and its free end to actuate the same for holding said gripping device in gripping or non-gripping position as the case may be, substantially as set forth.
2. In a belt buckle, a plate having upturned ears, a curved gripping device having a pivot bearing integrally formed at one side thereof between its longitudinal edges and having slots therethrough, a pin mounted in said ears and pivotally mounted in said pivot bearing, a loop for attachment to one end of the belt and having eyes fitting over said pin and in said slots and having its arms adapted to engage the longitudinal edges of said gripping member to force it into gripping engagement or nongripping engagement, substantially as set forth.

3. In a belt buckle, a front plate, a gripping device formed of sheet material having bearings formed by outwardly extending projections and having inwardly extending projections integrally curved therein and each having a pivot opening therethrough, said gripping device having slots therethrough adjacent said inward projections and having longitudinal edges, a pivot pin mounted in said plate, a loop shaped actuating member adapted for attachment to the belt and having eyes in its ends adapted to rest in said slots and engage said pin and having its arms adapted to engage the longitudinal edges of said gripping device to force it into gripping or out of gripping position as desired.

4. In a belt buckle, a concave shaped channeled plate having ears at each side adjacent one end, a pivot pin mounted in said ears and adapted to be securely held therein, an eccentrically mounted gripping device having longitudinal edges spaced apart from each other and pivotally mounted on said pin between said longitudinal edges, a loop shaped actuating member adapted to be attached to the belt and having eyes in its ends adapted to engage said pivot pin whereby the arms of said loop are adapted to positively operate said gripping device, substantially as set forth.

LAWRENCE F. OTTEN.
